UNITED STATES PATENT OFFICE.

RODEN L. BECK, OF INDEPENDENCE, KANSAS.

ACETYLENE-GAS GENERATOR.

1,101,237.

Specification of Letters Patent. Patented June 23, 1914.

Original application filed February 26, 1913, Serial No. 750,875. Divided and this application filed July 5, 1913. Serial No. 777,490.

To all whom it may concern:

Be it known that I, RODEN L. BECK, a citizen of the United States, residing at Independence, in the county of Montgomery and State of Kansas, have invented a new and useful Acetylene-Gas Generator, of which the following is a specification.

The device forming the subject matter of this application is a series of carbid-holding cells, adapted to be employed in an acetylene gas generator.

The invention hereinafter set forth constitutes matter divided out of my prior application No. 750,875, filed on or about February 26, 1913, and purporting to set forth sundry improvements in an acetylene gas generator.

The present invention aims to provide novel means for supporting the carbid cells in superposed relation, and for securing an adequate circulation of water through the cells.

It is within the scope of the invention to improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings:—Figure 1 shows the invention in vertical longitudinal section, parts appearing in elevation; Fig. 2 is a transverse section; Fig. 3 is a sectional detail showing a portion of one of the carbid receptacles; and Fig. 4 is a bottom plan of one of the carbid receptacles.

In carrying out the invention there is provided a receiver 1 having an outer wall 2 and an inner wall 3, spaced apart, there being a water seal 4 between the walls 2 and 3. The inner wall 3 defines a compartment 5 in which are located a plurality of superposed carbid receptacles 6. Each carbid receptacle is in the form of a frusto-conical pan equipped at its lower end with outstanding ears 7, whereby one pan may

be supported upon another. Each pan or carbid receptacle 6 is provided adjacent its upper edge and in its side wall with a water outlet 8. A closure 9 for the receiver 1 is provided, the closure being equipped with a depending side wall 10 which fits into the water seal 4 and lies between the walls 2 and 3 of the receiver 1. An upright pipe 11 is provided, the lower end of the pipe 11 being connected detachably with the closure 9 through the medium of a coupling 12. If it is desired to have the closure 9 rise and fall, the pipe 11 may be of a telescoping or flexible construction. If, however, it is desired that the closure 9 be held rigidly in place, the pipe 11 may be rigid so as to prevent the closure 9 from rising. A water supply pipe 38 enters the pipe 11. Water is supplied to the pipe 11 through the pipe 38, the water being discharged by the pipe 11 into the uppermost carbid receptacle 6, and when this receptacle 6 has filled sufficiently, water will flow downwardly through the outlet 8 and pass to the next lower carbid receptacle, the operation above described being carried out repeatedly, as one carbid receptacle after another is filled. The gas generated from the carbid will pass upwardly through the pipe 11. The opening 8 in each pan 6 is spaced sufficiently from the upper edge of the said pan, so that the water proceeding through the outlet 8 will be received within the contour of the next lower pan.

Having thus described the invention, what is claimed is:

In a device of the class described, a receiver; inverted, frusto-conical carbid receptacles in the receiver and arranged in superposed relation, each receptacle having an opening in its side wall and discharging into the next lower receptacle; and a plurality of brackets carried by each receptacle, each bracket comprising a slanting arm secured to the outer wall of one receptacle and a horizontal arm flush with the lower face of said receptacle, the horizontal arm projecting beyond the periphery of the larger end of said receptacle and engaging the upper edge of the larger end of the next lower receptacle, the extremities of the horizontal arms engaging the inner wall of the receiver to space the peripheries of the receptacles from the receiver, the horizontal

arms being visible as one receptacle is placed upon another, whereby the horizontal arms of the respective receptacles may be alined, thereby to effect an adjustment in the relative positions of the openings in the several receptacles; and means for admitting water to the uppermost receptacle.

In testimony that I claim the foregoing as my own, I have hereto affixed my signature in the presence of two witnesses.

RODEN L. BECK.
